INVENTOR:

Max Paul Ernst Hohn

By *Samuel K.*
Attorney,

UNITED STATES PATENT OFFICE

MAX PAUL ERNST HOHN, OF DRESDEN, GERMANY, ASSIGNOR TO UNIVERSELLE CIGARETTENMASCHINEN-FABRIK J. C. MULLER & CO., OF DRESDEN, GERMANY

DETECTING DEVICE FOR CIGARETTE TURNING MACHINES

Application filed November 5, 1931, Serial No. 573,243, and in Germany March 5, 1931.

It is already known, for turning incorrectly lying cigarettes into their face upward position during their feed from the cigarette machine to the packing machine to employ 5 feelers, pawls or the like, which rest against the seam and thus cause the cigarette to be adjusted into the correct position. For example, this is effected by the feeler or pawl being driven by the travelling cigarette, thus 10 setting into operation mechanically, electrically, pneumatically or in any other manner, a reversing device for the cigarette in question, or by the feeler moving against the cigarette to effect such release or by the feeler 15 rotating the cigarette directly and thereby initiating the turning thereof, or finally by rotating the cigarette against the stationary feeler until the seam comes against the feeler. In all these instances, it was cus- 20 tomary to employ thin metal springs or the like as feelers, the said feelers having a certain width to obtain a surer engagement.

It has now been found that, with such feelers consisting of broad, thin springs, errors 25 may occur in exploring, in that a smooth passage is provided at one point on the seam, perhaps due to exuded adhesive or the deposition of a grain of dust, or the like, on which the pawl or feeler slides without engaging 30 the seam. It is sufficient, of course, if only one narrow strip of the feeler is passed over the seam, because the feeler is comparatively rigid over its entire width.

The object of the present invention is to 35 obviate this disadvantage and to provide a feeler which is effective in all cases, even when there is to some extent a smooth passage on the explored place of the cigarette, i. e. when the front end of the overlapping 40 paper is not sufficiently free as to provide an abutment for the feeler. For this purpose, the feeler according to the invention, is formed of small individual fine rods which are arranged adjacent one another along the 45 requisite width of the feeler. Preferably, bristles will be employed for this purpose although, of course, other substances of like stiffness and strength may be used. Glass threads or metal threads may also be used, 50 for example, although with the latter there

is a greater risk of the paper being torn than with bristles.

One constructional form of the invention is shown by way of example in the drawing, 55 wherein:

Figure 1 is a side elevation of that part of the cigarette conveyor which is under consideration, and

Figure 2 is a view of a detail on an enlarged scale. 60

In the drawing, *a* is the cigarette conveyor, preferably consisting of chain links. The chain runs at one side over a sprocket wheel *b*, the sprocket wheel on the other side not being shown. The cigarettes lie singly in troughs of the chain and pass between profiled rolls *c* and *d*, the peripheral speed of which corresponds to the forward movement of the chain. In addition the two rolls *c* and *d* have the same peripheral 65 speed, so that the successive cigarettes conveyed by the chain *a* are held consecutively between the troughs of the rolls *c* and *d*, the said troughs supplementing one another to form a complete sheath. While the cigarette 70 is held in the manner described, it is engaged by the feeler. In the constructional example shown, a lever *e* is provided, which is pivotally mounted on a pin *f* on a lever *g* which latter in turn, is pivotally mounted 75 on a pin *h* on one end of a double lever *i* which swings about a pin *k* on the machine frame, and which carries on its free end a stop screw *m* bearing against the machine frame. The lever *g* carries a roller 80 *g*¹ and is so moved by a spring *n* that the roll- or *g*¹ rests against the periphery of a cam disc *o*. The lever *e* carries a roller *e*¹, which in turn is held by a spring *p* against the periphery of a cam disc *q*. The cam discs have each 85 four cam rises and they have to rotate at a speed such that, on the conveying of one cigarette, the two discs will have rotated through a quarter of a revolution, i. e. 90 through one cam division. The bracket *s* for the actual feeler is attached to the front end of the lever *e* and swings about a pin *r*. The 95 said feeler consists of bristles *t*, carried by a holder *u* and gripped between two clamping elements *v*. A spring *w* holds the bracket 100

8 with the bristles in the position shown in Figure 2, in which position, due to the provision of the spring *w*, the bristles yieldingly engage the front edge of the cigarette. A support *v*, engaging below the bristles secures 5 the bristles against downward sliding.

Accordingly the device so operates, that, each time a cigarette passes between two congruent troughs of the discs *c* and *d*, the feeler executes a downward movement and then a 10 movement towards the front edge of the seam to explore the latter. If the feeler thereby engages the seam, the whole of the feeler head will rock about the pivot *r*, thereby closing in known manner an electrical contact or 15 releasing a mechanical or pneumatic relay which causes the turning of the cigarette in question. The feeler *t* preferably consists of animal bristles of suitable stiffness, for example badger hair may be used for the purpose, but of course, other artificial materials, for example, glass hair or also very fine wires of a suitable metal or the like may be 20 used, although animal bristles have been found to be most suitable.

25 I claim:

1. A feeler for detecting incorrectly lying cigarettes in packing machines, comprising a brush which is adapted to engage the seam of an incorrectly lying cigarette.
2. A feeler according to claim 1, wherein the brush is composed of a plurality of animal bristles.
3. A feeler according to claim 1, wherein 35 the brush is composed of a plurality of badger hairs or bristles.

In testimony whereof I have affixed my signature.

MAX PAUL ERNST HOHN.
